ABSTRACT OF THE DISCLOSURE

A light power absorbing load consists of a low loss dielectric insulating insert in a tank. The tank is larger than the insert so that liquid in the tank has access to the surface of the insert. The insert thus serves to guide radio frequency power to the liquid in the tank.

This invention relates to liquid power-absorbing loads and whilst primarily concerned with liquid power-absorbing loads for absorbing unwanted power it is also applicable to liquid power-absorbing loads for measuring power by calorimetric effects.

As at present known, the usual liquid power-absorbing load consists of a length of waveguide, normally some two or three feet long, with a glass tube running down the middle of it, power-absorbing liquid (usually water) being pumped through the tube via input and output water connections at its end. Not only is the glass tube itself, mounted in this position, necessarily fragile but the water connections which pass through the waveguide to its exterior are also liable to be broken. Another defect is that there is a tendency for steam to be evolved in the conduit and if this happens it may seriously impair the power-absorbing capabilities of the load.

The present invention seeks to provide improved liquid power-absorbing loads in which the foregoing disadvantages are overcome or reduced.

According to this invention a liquid power-absorbing load comprises a low loss dielectric insulating insert in a tank the volume of which is large relative to the volume of said insert and the liquid in which has free access to the surface of the insert inside the tank, said insert serving to guide radio frequency power to the liquid in the tank.

The insert is within a length of perforated waveguide which is inside the tank, the perforations providing the liquid in the tank with free access to the surface of the insert in said tank.

Preferably again said body is of tapered form to provide a suitable shape for boundary of the liquid to which the power to be absorbed is applied.

Preferably again the body extends into the tank from within a choke waveguide section which is sealed into one wall of the liquid container.

Where the power to be absorbed is propagated in a rectangular waveguide a transformer wave guide section is preferably interposed between the choke waveguide section and the rectangular waveguide in order to achieve good matching.

2

The liquid container may be open to the atmosphere but in practice the container preferably is sealed and a vapour condenser is provided to condense any vapour evolved as a result of a rise in temperature of the liquid and return the vapour as liquid to said container.

The load may be employed simply to absorb unwanted power or it may be used as a calorimetric power measuring device.

The invention is illustrated in and further described with reference to the accompanying drawing which is a sectional view of a water power-absorbing load in accordance with the present invention.

Referring to the drawing the load consists of a Chebycheff waveguide transformer section 1 which is stepped in its E dimension only. The input end 2 of the transformer section 1 is provided with a rectangular flange to which a rectangular waveguide (not shown) transmitting radio-frequency power to be absorbed in the load may be attached. The waveguide transformer section 1 feeds into a dielectric filled choke section 3 which is sealed into the wall of a water-filled tank 4. Extending into the tank 4 from within the choke section 3 is a generally rectangular sectioned tapered insert 5 of P.T.F.E. or other low loss dielectric insulating material which reduces in cross-section, as shown, along its length from the choke section 3 to maintain a suitable shape for the boundary of the water to which the R.F. power to be absorbed is applied. The insert 5 is surrounded by a length of rectangular waveguide 6 all four walls of which are perforated to provide the water in the tank with free access to the surface of the insert 5. Sealing against water from the tank 4 entering the transformer section 1 along the tapered insert 5 is provided by O-rings shown at 7.

The tank 4 may be open to the air so that any steam evolved may freely escape or it may be sealed and a steam condenser 8 provided to condense any steam and return it to the tank as water.

Although the example described above is for absorbing power propagated in a waveguide, as will be understood, with suitable modification it may equally be used to absorb power propagated along a co-axial conductor.

We claim:

1. A power absorbing load arrangement comprising a container, a liquid within said container, a low loss dielectric insert in said container, and a length of perforated waveguide inside said container and surrounding said insert, the volume of said container being large relative to the volume of said insert, and said liquid having free access to the surface of the insert inside the container through said length of perforated waveguide, whereby the insert serves to guide radio frequency power to the liquid in the container.

2. A power absorbing load arrangement as claimed in claim 1 and wherein said insert is of tapered form to provide a suitable shape for boundary of the liquid to which power to be absorbed is applied.

3. A power absorbing load arrangement as claimed in claim 1 and wherein the insert extends into the container from within a choke waveguide section which is sealed into one wall of the container.

4. A power absorbing load arrangement as claimed in claim 3, and wherein power to be absorbed is propagated in a rectangular waveguide, and including a transformer

waveguide section interposed between the choke waveguide section and the rectangular waveguide in order to achieve good matching.

5. A power absorbing load arrangement as claimed in claim 1 and wherein the container is sealed and a vapour condenser is provided to condense any vapour evolved as a result of a rise in temperature of the liquid and return the vapour as liquid to said container.
